UNITED STATES PATENT OFFICE.

EDWARD W. NEWELL, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

PERCUSSION-FUSE FOR PROJECTILES.

1,309,768.

Specification of Letters Patent.

Patented July 15, 1919.

Application filed March 3, 1917. Serial No. 152,222.

To all whom it may concern:

Be it known that I, EDWARD W. NEWELL, a citizen of the United States, residing at Pittsburgh, in the county of Allegheny and State of Pennsylvania, have invented new and useful Improvements in Percussion-Fuses for Projectiles, of which the following is a specification.

This invention relates to percussion fuses, and more particularly to the type adapted to be employed in connection with projectiles which are detonated by impact.

The principal object of my invention is to provide a percussion fuse of the above character of few parts and adapted to be cheaply manufactured.

Other objects and advantages will appear in the following more detailed description of the invention.

20 In the accompanying drawing; Figure 1 is a central sectional view of a percussion fuse embodying my invention and applied to a projectile, showing the parts in normal position; Fig. 2 a similar view, showing the parts as positioned just after impact of the projectile; Fig. 3 an elevational view of the trip member for the firing plunger; and Fig. 4 an end view thereof.

According to my invention, a cage 1 is 30 provided, having a primer 2 mounted at the rear end thereof and adapted to be screwed into the forward end of the projectile body 3.

Within the cage 1 there is mounted a firing plunger 4, positioned to strike the primer 2 when released, and preferably cup shaped to contain a coiled spring 5 having its outer end abutting the interior wall of the nose 6 of the projectile, the spring being 40 held in position by a rod 7 screwed into the nose 6.

For effecting the retraction of the firing plunger 4 and the compression of spring 5 upon impact of the projectile a longitudinally movable inertia member 8 is provided having a plurality of resilient wings 9, positioned as shown in Fig. 3 when not restrained.

The wings 9 are provided with inwardly 50 extending flanges 10 at the inner ends for engaging over the inner end of the plunger 4.

The parts are assembled by placing the spring 5 and the firing plunger 4 in position on the nose 6 and then the inertia member 8 is placed over the firing plunger, so that the flanges 10 are in front of the end of the plunger. The cage 1 is then screwed into the nose 6, having first compressed the wings 9 so that they can enter the reduced bore 60 11 of the cage.

The cage is now screwed into the projectile body 3, the parts being positioned as shown in Fig. 1.

When the projectile is fired and hits, the impact thereof causes a forward movement of the inertia member 8, carrying with it the firing plunger 4 and thereby compressing the spring 5.

As the member 8 moves outwardly, the 70 flanged ends of the wings 9 are freed from the restricted bore 11 of the cage and fly out into an enlarged bore 12 thereof, so that the flanges 10 are freed from engagement with the end of the firing plunger and said 75 plunger being released, is shot rearwardly by the action of the compressed spring 5, so as to strike the primer 2 and thus detonate the projectile.

The opening formed by the flanges 10 for 80 the passage of the plunger may serve as a guide for the plunger, if desired.

The improved fuse mechanism is also adapted to be employed in connection with torpedoes, since the construction is water 85 tight.

Having now described my invention, what I claim as new and desire to secure by Letters Patent, is:

1. In an explosive projectile, the combination with a body portion and a nose, of a fuse mechanism mounted therein and comprising a firing plunger, a spring acting on said plunger, and a member movable by inertia upon impact of the projectile for first retracting the plunger to compress said spring and then adapted to release the plunger, thereby permitting the reverse movement of the plunger by the spring. 90 95

2. In an explosive projectile, the combination with a body portion and a nose, of a fuse mechanism mounted therein and comprising a firing plunger, a spring acting on said plunger, and a member movable by 100

inertia upon impact of the projectile for retracting the plunger to first compress said spring and then adapted to release the plunger to permit movement thereof by the 5 spring.

3. In an explosive projectile, the combination with a body portion and a nose, of fuse mechanism comprising a firing plunger, a spring mounted between the nose and said 10 plunger, and a movable member normally engaging said plunger and operated by inertia upon impact of the projectile for moving said plunger to compress the spring, said member being released from engagement

with the plunger near the end of its move- 15 ment.

4. In an explosive projectile, the combination with a body portion and a nose, of fuse mechanism comprising a firing plunger, a spring mounted between the nose and said 20 plunger, and a member provided with spring wings, normally confined to engage said plunger and adapted to release the plunger upon movement by inertia under impact of the projectile. 25

In testimony whereof I hereunto set my hand.

EDWARD W. NEWELL.
